UNITED STATES PATENT OFFICE.

OSCAR E. CHANEY, OF STEUBENVILLE, OHIO, ASSIGNOR OF ONE-HALF TO PAUL LORETTA, OF STEUBENVILLE, OHIO.

GAS-HEATER.

1,150,998.

Specification of Letters Patent. Patented Aug. 24, 1915.

Application filed August 14, 1914. Serial No. 856,830.

To all whom it may concern:

Be it known that I, OSCAR E. CHANEY, a citizen of the United States, residing at Steubenville, in the county of Jefferson and 5 State of Ohio, have invented certain new and useful Improvements in Gas-Heaters, of which the following is a specification.

This invention relates to new and useful improvements in gas burning heaters or 10 stoves and as its principal object aims to provide a heater the parts of which are arranged to attain a maximum air consuming capacity for the heater whereby the combustion of the gases is as nearly complete 15 as possible and the thermal efficiency is relatively high.

An additional object is to construct the 20 heater with such regard to number, proportion and arrangement of parts that it may be cheaply manufactured, will be durable and efficient in its action, and wherein access 25 to the interior of the heater may be easily had for cleaning purposes.

A further object is to so construct the 30 stove that it is provided with three independent air chambers all of which are heated by a gas burner tube located in one of the chambers and serve to develop a relatively large volume of heated air which will, 35 because of the particular arrangement of the air chambers, continuously pass out into the room wherein the heater is used.

The above recited and other incidental objects of a similar nature, which will be hereinafter more specifically treated, are accomplished by such means as are illustrated in the accompanying drawings, described in the following specification, and then more particularly pointed out in the claims, which 40 are appended hereto and form a part of this application.

With reference to the drawings, wherein 45 there has been illustrated the preferred embodiment of this invention as it is reduced to practice, and throughout the several views of which similar reference characters designate corresponding parts—Figure 1 is a perspective view of the heater; Fig. 2 is a vertical section taken medially through the 50 heater as disclosed in Fig. 1; Fig. 3 is a top view; and Fig. 4 is a section on the line 4—4 of Fig. 2.

In the embodiment of my invention illustrated in the accompanying drawings and in

Fig. 1 thereof particularly, the heater consists essentially in a body casing 10 within which are positioned a removable casing 11 and a burner tube 12. The body casing 10 is preferably, although not necessarily, substantially rectangular in shape, and is 50 formed from relatively light sheet metal. The side walls 13 and 14 of the casing are separately formed, and are connected at their upper terminals by a top plate 15 and at their lower terminals by a bottom wall 16. 55 The member 15 is in width considerably less than the side walls so that a relatively large opening 17 is defined between the inner edge of the member 15 and the face plate 18 which connects the forward edges 70 of the side walls adjacent their upper terminals. The upper edges of the side walls and the member 18 are directed outwardly to form ledges or flanges 19 which serve as retaining members for the cover 15'. As is 75 shown particularly in Fig. 2, this cover plate is provided at its forward edge and at its side edges with inwardly directed flanges 15'' which are engageable with the flanges 19 and serve to hold the cover against accidental displacement. Inasmuch as the flanges 15'' are freely engaged with the flanges 19, the cover 15' may, of course, be removed for cleaning purposes or for permitting the removal of the inner casing 11. 80 The member 18 is secured to the stove by bending its terminals at right angles and riveting them as at 20 to the side walls. The front and rear longitudinal edges of each side wall 13 and 14 are bent at right angles 85 and directed inwardly to form the vertical wings 21 and 22. To the vertical wings 22 of the side walls are secured, as by rivets or similar fastening means, the rear wall or back 22', which member is also formed of 90 sheet metal. The members 21 of the two side walls are provided at their front edges with right angularly extending flanges 23 to which are riveted, as at 24, the edges of a substantially U-shaped partitioning member 95 25. This partitioning member forms in connection with the side walls 13 and 14 and rear wall 22' a substantially U-shaped air chamber A. The bottom wall 16 is provided with a plurality of air openings or vents 100 16' which admit the air into the chamber A at the bottom thereof. The manner in 105 which the air is adapted to be heated and

circulated into the room will be hereinafter more fully discussed in that portion of the specification devoted to a description of the operation of the stove.

5 Through the rear wall 22' and traversing the air chamber A, is a stove pipe 26 the inner terminal of which is bent outwardly as at 27 to form a flange which may be riveted as at 28 to the inner face of the transversely extending wall 29 of the partition 25. On each side of the flange 27 there is attached to the inner face of the wall 29 and in vertical position thereon a pair of spacing webs or plates 30 which are substantially L-shaped in cross section and are secured by rivets or similar fastening devices 31. These members 30 are arranged in parallel spaced relation and serve to space the rear wall 32 of the removable casing 11 from the wall 29 of the partitioning member. It is now to be noted that the removable casing 11 is substantially rectangular and includes the rear wall 32, front wall 33 and end walls 35 and 36. The member 11 is open both at the top and bottom and is arranged with its lower terminal in communication with a transverse slot 37 formed in the bottom wall 16 adjacent the rear edge thereof.

Referring now to Fig. 2 it will be seen 30 that air may enter the slot 37 and after passing through the casing 11 exit into the U-shaped air chamber A. The upper terminal of the casing 11 carries a closure plate 38 which is in length approximately equal 35 to the distance between the side walls of the member 25 and is of a width equal to the distance between the member 18 and the upper edge of the wall 29. The member 38 is fixed with respect to the upper terminal 40 of the casing 11 and is adapted to be removed from the heater or applied thereto as a part of the casing. It is now to be noted that the wall 29 is arranged diagonally with respect to the vertical axis of the 45 heater and that the width of the air chamber A thus increases as it approaches the upper end of the heater.

The casing 11 is normally held in engagement against the spacing webs or plates 30 by means of a pair of holding plates 39 and 40 which members are substantially L-shaped in cross section and are secured by rivets 41 to the side walls 42 and 43 of the partition 25. The lateral portions of these 55 members 39 and 40 are arranged in parallel spaced relation to the member 29. It will thus be seen that the removable casing 11 is supported within the heater at an acute angle to the vertical axis thereof. The purpose for which this structure is deemed advisable will be hereinafter more fully explained.

It is now to be observed that a second U-shaped air chamber, designated by the letter B, is defined by the casing 11 in connec-

tion with the members 39 and 40 and the partition 25. This air chamber B communicates with the combustion chamber C of the heater through openings 44 which are formed between the upper edges of the members 39 and 40 and the closure plate 38. Within the combustion chamber C is secured the burner tube 12. This member 12 is formed from a sheet of metal rolled into annular form and punched in a number of places to produce the apertures 45. The tube 12 is supported by means of a transversely arranged bracket plate 46 in spaced relation to the bottom wall 16 as best shown in Figs. 1 and 2. A gas pipe 47 is extended through the bottom wall 16 and leads into the tube 12 for the obvious purpose of supplying gas thereto.

On the front wall 33 of the removable casing are arranged a series of baffle plates 48. 85 These members 48 are transversely curved and are arranged in transverse series, the individual baffle plates of each series being oppositely disposed with respect to the plates of the adjacent series as will be readily seen upon reference to Fig. 1. A pair of baffle plates 49 similar to the members 48 are also carried by each of the members 39 and 40. The baffle plates 48 and 49 may be secured by any suitable fastening means, 95 rivets being preferably employed. A hood indicated at 50 is formed on the lower edge of the member 18 and serves as will be hereinafter explained, to prevent the escape into the room of an undue proportion of 100 the air heated within the combustion chamber C by the burning gases of the tube 12.

The heater may be properly supported above the floor by means of legs 51 so as to admit air into the air vents 16'. At the 105 upper terminals of the side walls 13 and 14 are formed a number of air vents indicated at 53.

The construction and arrangement of the parts of the heater being thus disclosed, I 110 will now explain the manner in which the air in the various air chambers is heated and circulated from the stove.

When the burner tube 12 is lighted the air contained within the combustion chamber C is, of course, immediately heated to a relatively high temperature. At the same time the side walls 42 and 43 of the partitioning member 25 and the forward wall 33 of the removable casing 11, as well as the holding plates 39 and 40, are heated to a considerable temperature. As a result of the heating of the members 42 and 43 the air within the chamber A is raised in temperature, and inasmuch as air enters through the lower air vents 16' it is obvious that there will be a continuous circulation of air upwardly through the chamber A with the result that heated air will constantly issue from the air vents 53 into the room. Also 130

the cold air entering through the slot 37 will, in passing upwardly through the removable casing 11, be heated and will circulate through the member 11 and into the 5 chamber A at the upper terminal thereof. The heating of the air within the chamber A and within the removable casing 11 is considerably supplemented by the heated air and unburned gases which pass from the 10 combustion chamber C through the openings 44 and into the chamber B. This chamber B forms, as will now be obvious, the communicating passage between the combustion chamber C and the stove pipe 26. It 15 should now be noted that the lower ends of the members 30 terminate a slight distance above the bottom wall 16 so that the products of combustion passing from the combustion chamber C through the openings 44 20 will be carried downwardly through the chamber B to the lower terminal thereof, and will then proceed upwardly through the space defined by the members 30 and then outwardly through the pipe 26. Thus, while 25 the unburned gases of combustion are safely conducted from the heater so as not to escape into the room, they are utilized in their exit to supplement the heating action of the burner in raising the temperature of the air 30 within the removable casing 11 and the chamber A.

In concluding the description of my invention, I desire to direct particular attention to the fact that the heater is relatively 35 simple in construction and may, therefore, be manufactured and sold at a relatively cheap price.

The baffle plates above described serve to set up conflicting currents of air in the 40 combustion chamber C so that the mixture of the gas and the air is more thorough, with the result that the combustion of the gases is as nearly complete as possible. These baffle plates also, by setting up conflicting 45 currents, effect a uniform distribution of heat within the combustion chamber.

In reduction to practice, it has been found that the form of this invention illustrated in the drawings, and referred to in the 50 above description as the preferred embodiment, is the most efficient and practical; yet realizing that the conditions concurrent with the adoption of this device will necessarily vary, it is desirable to emphasize the fact 55 that various minor changes in details of construction, proportion and arrangement of parts may be resorted to, when required, without sacrificing any of the advantages of this invention, as defined in the appended 60 claims.

Having thus described the invention, what is claimed as new is:

1. A gas heater including a combustion chamber, a burner arranged therein, an air 65 chamber surrounding the combustion cham-

ber on three sides, and a removable casing defining an air chamber located within the limits of the first-mentioned air chamber and in the rear of the combustion chamber.

2. A gas heater including a combustion 70 chamber, a burner arranged therein, a substantially U-shaped air chamber inclosing the combustion chamber on three sides, a second substantially U-shaped air chamber of less dimensions than the first-mentioned 75 air chamber arranged in the rear of the combustion chamber and within the limits of the first-mentioned air chamber, and a stove pipe extending through the first-mentioned air chamber and leading into the second- 80 mentioned air chamber, there being openings in the combustion chamber affording communication between the combustion chamber and the second-mentioned air chamber at the upper terminals thereof. 85

3. A gas heater including a body casing, a substantially U-shaped partition arranged within the body casing and defining in connection therewith a substantially U-shaped air chamber, there being openings formed in 90 the bottom of the casing to admit air into the said chamber, a removable casing arranged within the partition member and defining in connection therewith a second substantially U-shaped chamber which is of less 95 dimensions than the first-mentioned air chamber and is located within the limits thereof, said casing, side walls and partition member defining a combustion chamber, a burner arranged in the combustion chamber, 100 and a plurality of baffle plates carried by the removable casing.

4. A gas heater including a body casing, a U-shaped partition arranged therein and defining in connection therewith an interior 105 U-shaped air chamber, a substantially rectangular casing removably mounted in the heater and disposed within the partition to define in connection therewith a substantially U-shaped interior air chamber, there 110 being a combustion chamber at the front of the heater, and openings affording communication between the combustion chamber and the interior air chamber.

5. A gas heater including a body casing, a U-shaped partition arranged therein and defining in connection therewith an interior 115 U-shaped air chamber, a substantially rectangular casing removably mounted in the heater and disposed within the partition to define in connection therewith a substantially U-shaped interior air chamber, there being a combustion chamber at the front of the heater, and openings affording communication 120 between the combustion chamber and the interior air chamber, said interior air chamber and removable casing being both 125 communicant with the atmosphere but being non-communicant with respect to the interior U-shaped air chamber. 130

6. A gas heater including a body casing, a U-shaped partition arranged therein and defining in connection therewith a U-shaped air chamber, a combustion chamber located within said air chamber, and a removable rectangular casing arranged within the said partition and defining an air chamber which is located at the rear of the combustion

chamber and is open to the atmosphere for free circulation of air.

In testimony whereof I affix my signature in presence of two witnesses.

OSCAR E. CHANEY. [L.S.]
